(57) CLAIM

The ornamental design for a grater, as shown and described.

DESCRIPTION

FIG. 1 is a top plan view of a grater according to the design;
FIG. 2 is an elevational view of one side of the FIG. 1, (the
other side corresponds to this side);

FIG. 3 is a bottom plan view of the grater of FIG. 1; and,
FIG. 4 is an elevational view of one end of the FIG. 1, (the
other end corresponds to this end).
